UNITED STATES PATENT OFFICE.

EDWARD LAAS, OF ELGIN, AND HIRAM H. SPONENBURG, OF WADSWORTH, ILLINOIS.

RAILWAY-RAIL STAY.

SPECIFICATION forming part of Letters Patent No. 779,086, dated January 3, 1905.

Application filed May 2, 1904. Serial No. 205,891.

To all whom it may concern:

Be it known that we, EDWARD LAAS, of Elgin, in the county of Kane, and HIRAM H. SPONENBURG, of Wadsworth, in the county of Lake, 5 in the State of Illinois, have invented new and useful Improvements in Railway-Rail Stays, of which the following, taken in connection with the accompanying drawings, is a full, clear, and exact description.

10 This invention relates to devices for preventing railway-rails from creeping longitudinally; and the invention has more particularly reference to the devices shown in our Letters Patent No. 720,362, dated February 10, 1903.

15 The object of our present invention is to provide the anticerping rail-stay with a more positive and secure grip for engaging the rail to be restrained from accidentally shifting or creeping longitudinally on its supporting 20 cross-tie; and to that end our invention consists in the improved construction and combination of the rail-gripping jaw and its seat upon the bracket or bar which abuts on the side of the cross-tie, all as hereinafter more 25 fully described.

In the annexed drawings, constituting part of this application, Figure 1 is a transverse section of a railway-rail equipped with our improved rail-stay. Fig. 2 is a plan view of 30 the same. Fig. 3 is a transverse section on the line X X in Fig. 2; and Fig. 4 is an enlarged horizontal sectional view of the rail-gripping jaw and adjacent portion of the rail, taken on the line Y Y in Fig. 1.

35 R represents the rail, which is supported on the cross-tie C in the usual manner.

The arrow N in Fig. 2 indicates the direction in which the rail tends to creep.

40 *a* designates the bracket or bar, which extends across the under side of the rail R and is formed with a hook or jaw *b*, which grips one of the flanges of the rail. The opposite end of the bar *a* has adjustably secured to it the jaw *c*, which grips the adjacent flange of 45 the rail.

Our present invention resides in the con-

struction of the jaw *c* and the means for sustaining the said jaw on the bracket or bar *a*. This jaw we form with a rail-gripping face *d*, which is serrated, so as to provide it with fine 50 teeth which bite into the edge of the rail-base and obtain a secure hold thereon, as illustrated in Fig. 4 of the drawings. Above the serrated gripping-face *d* is a lip *l*, projecting from the jaw and bearing on the top of the rail-flange.

To thoroughly brace the jaw *c* and increase its efficiency, we form the bar or bracket *a* with an upwardly-projecting shoulder *e*, on which the back of the jaw *c* abuts. The central portion of this shoulder *e* we form with a longitudinal segmental face *f*, preferably concave or of the form of a recess and with straight end faces *f' f'*, as shown in Fig. 4 of the drawings. The back of the jaw *c* is formed correspondingly and abuts on the aforesaid faces of the shoulder *e*.

The jaw *c* is provided with a vertical aperture *h*, which is in line with an aperture *h'* in the bracket *a*, and through the said apertures 70 passes the bolt *i*, which is provided with a head *j* on one end and with a nut *n* on the opposite end and firmly clamps the jaw on the bracket *a*.

o denotes a vertical flange which is formed 75 on the bracket *a* and bears on the side of the cross-tie C to prevent the rail from creeping endwise. A rib *o'*, formed on the bracket and on the flange *o*, serves to brace the said flange.

By leaving a slight space *t* between one of 80 the end faces *f'* and back of the jaw the jaw is allowed to slightly turn, and thereby cause the jaw to more firmly grip the rail when subjected to longitudinal strain.

What we claim as our invention is— 85

1. In combination with the rail and cross-tie, a bracket abutting on the side of the cross-tie and provided at one end with a rail-gripping jaw and at the opposite end with an upwardly-projecting shoulder formed with a 90 longitudinal segmental central portion in its face and with straight end portions on said

face, and a jaw adjustably secured to the bracket and formed with a corresponding outer face engaging the aforesaid shoulder.

2. The combination with the rail, of a bracket disposed to abut on the side of the cross-tie and provided at one end with a rail-gripping jaw and at the opposite end with an upwardly-projecting shoulder formed with a longitudinal segmental central portion in its 10 face and with straight end portions on said face, and a jaw adjustably secured to the bracket and formed with a serrated rail-grip-

ping face and with an outer face conformed to and engaging the aforesaid shoulder as set forth.

EDWARD LAAS.
HIRAM H. SPONENBURG.
